(57) **CLAIM**

I claim the ornamental design for a lure lock, as shown and described.

DESCRIPTION

FIG. 1 is a top view of the lure lock, shown enclosed around a fishing lure and a fishing pole;

FIG. 2 is a bottom view thereof;

FIG. 3 is a front view thereof;

FIG. 4 is a rear view thereof;

FIG. 5 is a side view thereof;

FIG. 6 is an opposite side view thereof;

FIG. 7 is a top perspective view of the design shown in use;

FIG. 8 is a front perspective view of the lure lock shown with the top open; and,

FIG. 9 is a front perspective view, with the top shown closed. The broken lines showing a fishing lure, fishing pole and fisherman are for illustrative purposes only and form no part of the claimed design.
